Primary Examiner — Catherine Tuttle*(74) Attorney, Agent, or Firm* — Jeffrey RoddyCLAIM

We claim the ornamental design for the soccer tee, as shown and described.

DESCRIPTION

FIG. 1 is a top perspective view of a first embodiment of a soccer tee showing our new design;

FIG. 2 is a bottom perspective view thereof;

FIG. 3 is a side elevation thereof;

FIG. 4 is a top plan view thereof;

FIG. 5 is a bottom plan view thereof;

FIG. 6 is a front elevation thereof;

FIG. 7 is a back elevation thereof;

FIG. 8 is a top perspective view of a second embodiment of the soccer tee;

FIG. 9 is a bottom perspective view thereof;

FIG. 10 is a side elevation thereof;

FIG. 11 is a top plan view thereof;

FIG. 12 is a bottom plan view thereof;

FIG. 13 is a front elevation thereof; and,

FIG. 14 is a back elevation thereof.
